UNITED STATES PATENT OFFICE.

LEOPOLD KAUFMAN, OF CINCINNATI, OHIO, ASSIGNOR OF ONE-HALF TO
HENRY HELLMAN, OF SAME PLACE.

ANTI-FRICTION JOURNAL-BEARING.

SPECIFICATION forming part of Letters Patent No. 249,948, dated November 22, 1881.

Application filed September 17, 1881. (No model.)

To all whom it may concern:

Be it known that I, LEOPOLD KAUFMAN, of the city of Cincinnati, county of Hamilton, and State of Ohio, have invented a new and useful 5 Improvement in Anti-Friction Journal-Bearings, of which the following is a specification.

My invention relates to the class of journals, boxes, bearings, and the like which embody anti-friction rollers; and it consists in a novel 10 combination and arrangement of anti-friction rollers and blocks, substantially in the manner hereinafter described and claimed.

My improvement may be applied to journals of any description where the friction is great 15 and where an anti-friction bearing is desirable; but for the purpose of my invention it is sufficient to illustrate it in connection with its application to the axle of a car, its application to other journals being obvious from such description.

In the drawings, Figure 1 is a perspective view of a car-axle box embodying my invention as seen from the outside; Fig. 2, a perspective of the same as seen from the inner 25 side; Fig. 3, a cross-section of the journal-box, showing the journal and bearings. Fig. 4 is a detail view of an upper or lower section of journal-box. Figs. 5, 6, and 7 are detail views of the journal, roller, and separating-block, respectively.

Similar letters of reference indicate corresponding parts.

A represents a car-axle.

D and E are inclosing-boxes secured within 35 an axle-box to the track-beams of a car, which boxes are recessed to form the seat and inclosing-case of a series of alternate rollers and separating-blocks, B and C, the flange at each end serving to prevent the endwise movement or 40 escape of such roller or blocks, as well as to retain a sufficient amount of oil to lubricate all the bearing-surfaces of the rolls, as well upon their ends as upon their peripheries.

B is a series of small rollers, which rest 45 closely in the inclosing-box and afford an anti-friction support for the axle, being separated from each other by non-rotating blocks concave on either side. The axle A is also countersunk to receive the rollers and separating-blocks,

its shoulders serving to further support them 50 against endwise movement. The rollers and separating-blocks are thus secured in position without any attachment, and may be removed and replaced independently. The separating-blocks are made of such dimensions that they 55 are supported by the rolls with their inner and outer longitudinal faces slightly out of contact with the journal and containing-box respectively, and thus are relieved from friction on either of these faces while revolving. This is 60 shown in Fig. 3.

In operation the rollers rotate to reduce the friction of the axle, while the rolls and separating-blocks also revolve continuously round the inclosing box. In their revolution they pass 65 through the lubricating-oil retained in the inclosing-box, and the entire bearing-surfaces of the rolls of the journal and of the blocks, both endwise and peripheral, are thus kept constantly lubricated. A difficulty arising where 70 the rollers have journal-bearings of their own is thus obviated.

I claim—

1. In a journal-bearing, the combination of a series of independent rollers and independent 75 non-rotating separating-blocks revolving about the journal, substantially as described.

2. In a journal-bearing, the combination of a series of independent rollers and non-rotating blocks revolving about the journal, with a 80 recessed box and countersunk journal, substantially as described.

3. In a journal-bearing, the combination, with the independent rolls and concave separating-blocks, of recessed inclosing-boxes adapted to 85 contain lubricants and apply them to the several bearing-surfaces in their revolution, substantially as described.

4. In combination with the independent rolls of a journal-bearing, the independent non-rotating separating-blocks sustained by the rolls out of contact with the bearing-surfaces of the journal and containing-box respectively. 90

LEOPOLD KAUFMAN.

Witnesses:

DANL. KELLY,
JOHN OELRING.
